GRADING ATTACHMENT FOR STEAM SHOVELS

Application filed August 31, 1931. Serial No. 560,463.

The invention relates to grading machines and more particularly to a machine adapted for sub-grading a road bed preparatory to the laying of a pavement thereon. In the present state of the art of concrete road construction it is usual to first establish the rough grade, then to lay form rails upon opposite sides of the roadway to limit the width of the pavement and also to form a track on which the cement laying mechanism can travel. However, after the setting of these form rails it is necessary to sub-grade so as to provide a foundation for the cement in predetermined relation to the plane of the upper face of the rails. Various devices have been used for effecting this sub-grading, such as scrapers or scarifiers operated by tractors. It is, however, the object of the present invention to accomplish the desired result by the use of a simple attachment to apparatus that is already upon the job. Thus in the original grading operation steam shovels are employed and my improvement consists in the use of the steam shovel together with a simple attachment for also effecting the sub-grading. To this end the invention consists in the construction as hereinafter set forth.

In the drawings:

Figure 1 is a cross section through a roadway illustrating my improved sub-grading apparatus in position for operation.

Figure 2 is a longitudinal section;

Figure 3 is a similar view showing the operation of transporting and dumping the load;

Figure 4 is a plan view of the apron.

As illustrated in Figure 1, A is the road bed after the first grading operation and B are the form rails which are placed in position at opposite sides of the road. After the placing of these rails the surface of the road between the same is still in an uneven condition, being high at certain points and possibly low at others, and therefore before the laying of the cement it is necessary to sub-grade, which I accomplish by the following construction. C are wheeled trucks adapted to engage the opposite form rails B and D is a cross beam connecting the truck C and ex-

tending above the intervening roadway. Suspended from the cross beam D is an apron E preferably of a width equal at least to one-half the width of the road or if desired it may be for the full width of the road. The forward edge F of this apron forms a cutting blade which is arranged at such an angle that there will be a slight tendency to draw downward or into the earth. The rear end of this apron is provided with a supporting shoe G which slides over the cut path and holds the apron at the desired angle. The apron E is provided with side flanges H which converge rearwardly and at their rear ends are adapted to engage the bucket I of a steam shovel. This bucket is supported by the usual beam J and is operated by the usual mechanism (not shown). The apron may be attached to the bucket by a clamping bar K which extends over the upper side of the bucket and is secured to the sides H of the apron by bolts L. Thus the apron is so attached to the bucket that it may be lifted therewith in usual operation of the steam shovel.

With the construction as thus far described, the operation is as follows: The apron E is first attached to the bucket of the steam shovel as previously described and its forward end is then suspended from the beam D by suitable suspension hooks L'. These are preferably provided with means such as the threaded bolts M and adjusting nuts N for raising and lowering the cutting edge F of the apron so as to arrange the same in the desired relation to the plane of the upper faces of the rails B. Assuming that one side of the road bed extends slightly higher than the plane of the cutting edge F, this is cut to the desired grade by driving the steam shovel forward which through its arm J and bucket I will propel the apron E and through the anchors L will also propel the beam D and trucks C during this movement the beam will hold the cutting edge F from moving downward while the angle of the apron is such as to avoid any tendency to rise upward or to ride over the earth. After the machine has been propelled a sufficient distance to load the apron with the removed earth, the steam shovel is moved backward a sufficient dis-

tance to clear the forward edge of the apron from the beam D after which the arm J is manipulated to raise the bucket and the apron and to dump the load wherever desired. In 5 case, as frequently happens, one side of the road bed is slightly below grade as indicated at O, the removed earth may be dumped in this low spot and subsequently graded by 10 passing the apron E over the same. If on the other hand there are no low places in the road bed the apron and bucket may be dumped at one side of the road.

One of the chief advantages of my construction is that the same device which is used 15 for cutting the earth to establish the sub-grade is also employed for transporting and dumping the removed earth. This greatly simplifies the operation over constructions where the earth is cut with one piece of apparatus and then the loosened earth must be 20 removed by other means. Another great advantage is that the steam shovel is already on the job and is available for this operation which avoids the necessity of providing trac- 25 tors or other equipment.

What I claim as my invention is:

1. The combination with a steam shovel 30 and the form rails of a pavement laying apparatus, of a grader comprising a wheeled frame adapted to travel on said form rails, an apron supported from said frame and having a forward cutting edge in predetermined relation to the plane of the rails, and means 35 for propelling said apron and frame from said steam shovel.

2. The combination with a steam shovel 40 and the form rails of a pavement laying apparatus, of a wheeled frame adapted to travel upon said form rails and extending across the intervening road bed, an apron detachably supported from said frame and having a forward cutting edge held in predetermined relation to the plane of said rails and means for attaching said apron to the bucket of a steam 45 shovel to be propelled thereby.

3. The combination with a steam shovel 50 and the form rails of a pavement laying apparatus, of a wheeled frame adapted to travel upon said form rails and extending across the intervening road bed, an apron detachably supported from said frame and having a forward cutting edge held in predetermined relation to the plane of said rails, means for attaching said apron to the bucket of a steam 55 shovel to be propelled thereby, and a shoe for supporting the rear end of said apron on the road bed and establishing a predetermined inclination to the forward cutting edge.

4. The combination with a steam shovel 60 and the form rails of a pavement laying apparatus, of a wheeled frame adapted to travel upon said form rails and extending across the intervening road bed, of an apron having a wide forward cutting edge with sides con- 65 verging rearwardly and adapted at their rear

ends to embrace and to be secured to the bucket of a steam shovel, and hooked anchors for supporting the forward portion of said apron in predetermined relation to the plane of said form rails permitting of disengagement of the apron from said frame to dump the load.

5. The method of subgrading the road bed 70 for pavements having pavement laying form rails on opposite sides thereof and a wheeled cross frame adapted to travel on said rails which consists in attaching a cutting apron 75 to the bucket of a steam shovel, supporting the cutting edge of said apron in predetermined relation to the plane of said rails by detachably supporting the same from said wheeled frame, propelling said apron and wheeled frame by the steam shovel and immediately lifting the apron by said bucket to remove and dump the load.

In testimony whereof I affix my signature.
